E. E. PIGG.
DOUBLE ACTION PUMP.
APPLICATION FILED JUNE 24, 1920.

1,417,105.

Patented May 23, 1922.

UNITED STATES PATENT OFFICE.

EDWARD E. PIGG, OF WEATHERFORD, OKLAHOMA.

DOUBLE-ACTION PUMP.

1,417,105.

Specification of Letters Patent. Patented May 23, 1922.

Application filed June 24, 1920. Serial No. 391,376.

To all whom it may concern:

Be it known that I, EDWARD E. Pigg, a citizen of the United States, residing at Weatherford, in the county of Custer and State of Oklahoma, have invented certain new and useful Improvements in Double-Action Pumps, of which the following is a specification.

This invention relates to new and useful improvements in double acting pumps, and more particularly to the portable hand pump used in connection with inflating pneumatic automobile tubes, the primary object of the invention being to devise an arrangement whereby air may be forced from the pump during either up or down stroke of the piston.

An important object of the invention is to provide an improved upwardly closing valve for the upper end of the cylinder which will be assisted in closing by the movement of the piston rod.

Another object of the invention is to provide a device of the above nature which is strong, durable, inexpensive to manufacture and highly efficient in practice.

Other objects and advantages of the invention will become apparent during the course of the following description.

In the accompanying drawings forming a part of the application and wherein like numerals are employed to designate like parts throughout the several views.

Figure 1 is a longitudinal section through the invention, and

Figure 2 is a longitudinal section through the upper end of the pump illustrating a modified form of valve.

Referring to the drawings wherein for the purpose of illustration are shown preferred embodiments of the invention, the numeral 3 designates a base which serves as a foot piece for maintaining the pump in a vertical position, and which is provided with a cavity or recess 4, the side walls of which closely fit against the exterior of the lower end of the pump cylinder 5. A disk 6 is fitted within the lower end of the pump cylinder and within the cavity 4 to provide the base with an annular channel 7 which receives the lower edge of a pump cylinder. The disk 6 is provided with a central opening 8, the walls of which flare outwardly and upwardly whereby a ball valve 9 may be received therein and close downwardly. A suitable cage 10 is fitted upon the upper end of the opening 8 to prevent displacement of

the ball valve 9 and a passage way 11 is provided in the base 3 to extend from the lower end of the opening 8 to the upper surface of the base whereby air may be sucked into the cylinder at the proper time.

Nipples 12 are provided for the upper and lower end of the cylinder and which extend outwardly of one side thereof then toward each other as clearly shown in the drawing. The outer edge of each nipple is provided with a valve seat whereby a ball valve 13 may close upwardly upon its seat and check valve 14 may close downwardly upon the seat of its respective nipple. A by-pass or pipe 15 is arranged vertically of the pump cylinder and in close relation thereto, opposite ends 16 of the pipe being enlarged to form a valve casing for the valves 13 and 14. Between the ends of this by-pass a flexible hose 17 is connected whereby air passing through either check valve may pass out through the hose 17.

A piston or plunger is adapted to reciprocate within the pump cylinder and consists of a piston head 18 formed from a plurality of alternately arranged superposed layers of rubber and steel disks arranged upon the lower end of the piston rod 19 and retained thereon by means of lock nuts 20.

The upper end of the pump cylinder 5 is exteriorly screw threaded for engagement with an interiorly depending screw threaded flange 21 of a cap or closure 22, the walls of which may converge upwardly and inwardly of the piston rod to terminate in a central opening or passage 23. This opening communicates with a chamber 24 formed within the cap by a partition 25 in the lower end thereof. A valve seat is provided centrally of the partition 25 and is formed by providing the central portion of the partition 25 with an annular upwardly and inwardly tapering flange 26 surrounding the central opening in the partition. This flange is provided with circumferentially spaced apertures 27 so that air may pass through the openings 23 of the cap into the chamber 24 and through the aperture 27 into the pump cylinder. In order to close the apertures upon the upstroke of the piston, the valve 28, preferably constructed of rubber, is mounted upon the piston rod and is provided at its lower end with a downwardly and outwardly flaring portion 29 which is adapted to seat upwardly upon the valve seat or within the annular flange 26. The valve 28 is tubular and is loosely mounted

upon the rod 19. The body portion 30 of the valve extends upwardly through the cap and opening 23 therein, and its upper end is exteriorly screw threaded so as to receive a 5 packing nut 31 containing packing 32.

From the foregoing, it will be obvious that upon the start of the down stroke of the piston, the valve 28 will be moved slightly downwardly through the cap by its contact 10 with the piston rod so as to unseat the valve 28 and permit of air passing through the opening 23 in the cap into the cylinder and thence through the apertures 27 in the flange 26 and then into the cylinder. The downward 15 movement of the valve will be checked by the nut 31 abutting with the top of the cap. The air will continue to be sucked into the upper end of the cylinder as the piston descends and the ball valve 9 will automatically close to prevent air from escaping 20 from the lower end of the cylinder through the passageway 11. Simultaneously, the check valve 13 will be sucked against the seat in the upper nipple 12 while the coacting 25 check valve 14 will open and permit air being forced out of the lower end of the cylinder through the nipple 12 and thence through the by-pass into the discharge hose 17. Upon upward stroke of the piston, the 30 inlet valve 9 will open while the check valve 14 will be drawn down against its seat and its coacting check valve 13 will be opened. The valve 28 of the cap will be caused to move upwardly against its seat by its contact with 35 the piston rod and the air being forced upwardly into the cylinder. Consequently, air will be forced out through the upper nipple 12 into the by-path 15 and thence into the discharge hose 17.

40 In the form of invention disclosed in Figure 2, I have provided a slightly different form of cap and valve, the cap 33 in the present instance being provided with the inlet opening 34 through which the piston rod 19 extends. It will be noted that the opening 45 34 is slightly larger in diameter than the piston rod and consequently air is admitted to the cap upon the down stroke of the piston. The lower end of the opening 34 flares outwardly as at 35 to provide the cap with a valve seat, and an upwardly moving valve 36 is mounted upon the piston rod whereby it will close upwardly upon upward movement 50 of the piston. The valve 36, like the valve 28 in the preceding form, is engaged around the piston rod so that it will not bind the movement of the rod when the same is seated.

The cap is provided with a depending cage 37 which is adapted to enclose the valve and 60 to prevent excessive downward movement thereof. The bottom of the cage is provided with a relatively large opening 38 through which extends the piston rod, and the sides of the cage are provided with a 65 plurality of apertures 39 to permit air en-

tering through the cap to pass into the cylinder.

From the operation of the preceding form and the construction of the modified form, it will be obvious that upon upward movement 70 of the piston, the valve will be caused to move vertically into engagement with its seat 35 to prevent the escape of air through the upper end of the cylinder. However, upon downward movement of the piston, the 75 valve 36 will move downwardly of its seat until it contacts with the bottom of the cage 38, whereupon further downward movement of the valve will be prohibited.

The foregoing description and the accompanying drawings have reference to the preferred or approved embodiment of my invention. It is to be understood however that such changes may be made in construction and arrangement of parts, materials, 85 dimensions, etc., as may prove expedient and fall within the scope of the appended claims.

Having thus fully described my invention what I claim as new and desire to secure by Letters Patent is:

1. A double acting pump comprising a cylinder, a by-pass communicating with the upper and lower ends of the cylinder and leading to a common outlet, a check valve at each end of the by-pass, an air inlet valve 95 for the lower end of the cylinder, a piston in the cylinder, a cap for the upper end of the cylinder through which the piston passes, an air inlet valve for the upper end of the cylinder frictionally mounted upon the upper end of the piston, and a partition carried by the cap and spaced from the top thereof for limiting the movement of the valve carried by the piston.

2. A double action pump comprising a 105 cylinder, a by-pass communicating with the ends of the cylinder, and leading to a common outlet, a check valve in each end of the by-pass, an air inlet valve for one end of the cylinder, a piston mounted in the cylinder, 110 a piston rod, a cap for the other end of the cylinder having an opening therein for the passage of said piston rod, a sleeve valve frictionally engaged with the upper end of the piston rod and adapted to extend through 115 the opening in the cap, a partition carried by the cap and having an opening therein for the passage of the rod and valve and adapted to restrict the outward movement of the valve, and the upper end of the valve being 120 enlarged to form an abutment adapted to contact with the cap for limiting the inward movement of the valve.

In testimony whereof I affix my signature in presence of two witnesses.

EDWARD E. PIGG.
